United States Patent Office

Des. 228,305

Patented Sept. 4, 1973

228,305

LANTERN

Robert D. Kahn, Rockville Centre, N.Y., assignor to
Fedtro, Inc., Rockville Centre, N.Y.

Filed July 3, 1972, Ser. No. 268,577

Term of patent 14 years

Int. Cl. D26—02

U.S. Cl. D48—24 R

F/G. 2

F/G. 1

FIG. 3

FIG. 4

FIG. 1 is a perspective view showing the front, top and right side of my new design for a lantern;

FIG. 2 is a rear elevation view thereof;

FIG. 3 is a left side view thereof (the right side being substantially identical thereto); and

FIG. 4 is a bottom plan view thereof.

I claim:

The ornamental design for a lantern, as shown and described.
